DESK LAMP OR THE LIKE

Arnold Goldstein, Allentown, Pa.

Application September 2, 1958, Serial No. 52,463

Term of patent 3½ years

(Cl. D48—20)

The dominant features of my design reside in the portions shown in full lines, with the standard fragmentarily shown in Figs. 3 and 4 and omitted in Figs. 5 and 6 for convenience of illustration.

I claim:

The ornamental design for a desk lamp or the like, substantially as shown and described.
